UNITED STATES PATENT OFFICE.

JAMES R. AVERY, OF LOUISVILLE, KENTUCKY.

CAR-COUPING.

SPECIFICATION forming part of Letters Patent No. 315,884, dated April 14, 1885.

Application filed July 3, 1884. (No model.)

To all whom it may concern:

Be it known that I, JAMES R. AVERY, a citizen of the United States, residing at Louisville, in the county of Jefferson and State of Kentucky, have invented a new and useful 5 Separable Coupling Combination, of which the following is a specification.

My invention relates to improvements in 10 couplings for street and railroad cars, engines, and tenders; and it consists in the combination of an automatic separable coupler, draw-bar, guide-rest, springs, and attachments.

In the accompanying drawings, Figure 1 is 15 a horizontal sectional plan of the separable coupling combination made in accordance with my invention. Fig. 2 is a vertical longitudinal section of the same. Fig. 3 is a perspective view of the coupling-head detached. Fig. 4 is a detail view of the draw-bar. Figs. 20 5 and 6 are detached views of the guide-rest and spring, respectively. Fig. 7 is a plan of the link. Fig. 8 is a perspective view of the entire combination.

A, Figs. 1 and 2, represents the coupler, made, 25 in accordance with my invention, of any suitable material, preferably of cast-iron, having a coupling-link, L, and pin P, the form and dimensions of which determine the configuration and dimensions of the coupler and its 30 cavities. The part A comprises a circular front with link-opening having quarter-circle walls A' and A² converging from the contour of said front and blending with the semicircle and three-quarter-circle walls of inner cavity, 35 a, of elliptical form, and link-rest a' of crescent form, for reception, guidance, entrance, elevation, and operation of the coupling-link, a pin-hole, H, for the reception and operation of the coupling-pin, and a seat, N, for its occupation preparatory to a coupling, a clutch 40 end separable device having three sections, D D' D'', of equal width and thickness, the upper and lower of equal length, and the center section about three times the length of either 45 with a vertical hole, O, through its center, or an equivalent device for convenient attachment and separation.

B represents the draw-bar, made, preferably, 50 of wrought-iron, in the form of a square-ended link or rectangled parallelogram doubled, providing vertical and horizontal openings d

d', each equal and bisecting the other longitudinally.

I is a guide-rest having three sides of a rectangled parallelogram fitted upon the vertical 55 end of the draw-bar with its parallel sides extending on each side, and secured thereto with the bar-key i passing through mortise-holes provided in said parallel sides immediately behind the vertical sections to which the angles of the guide-rest I are closely fitted, for 60 combination and other purposes hereinafter set forth.

S represents the springs, made of any suitable material, preferably of fine spring-steel 65 in crimp form, with depending right-angled ends, having a small hole through each for the reception of a small rod, p, or other equivalent device for securing it in the draw-bar. This rod p may also pass through a hole in 70 the key h, to secure it in place.

The devices for attachment to the car-frame are made of any suitable material, preferably of wrought-iron bars C C. These bars have front angles, 1 2 3, and rear angles, C' C'. In 75 the vertical sides of angles 1 and C' mortise-holes are provided to receive the tenons made on ends of the guide-bars g g, which are secured therein in a longitudinal vertical position. These bars have a mortise-hole through 80 each equally distant from corresponding angles 1 and C', for the reception and security of the co-ordinate bar U, having a mortise-hole through each end provided with pins, bolts, keys, or other fastenings. This co-ordinate 85 bar is provided with a mortise-hole through its center for the reception of the ends of the crimp-spring, as hereinafter more fully set forth.

R is a hanger or rest having the form of a 90 rectangled parallelogram, or other form conforming to the contour of the coupler, which is supported therein. Its purposes will more fully appear in the combination.

To combine, attach, and operate my separable coupling combination, place upon the end cross timber or bar provided for the purpose on each side, and equally distant from the central line of the car, engine, or tender frame, the angles 2 of the connecting-bar C C, 95 and upon the cross timber or bar provided in the rear of the first at a proper distance there-

from, and parallel thereto; place the angles C^2 parallel each to the other, with the angles 3 of each projecting in front of the front cross timber or bar sufficient to receive the hanger or 5 rest R, placed within said angles and depending therefrom, place draw-bar B, with guide-rest I secured thereto, between guide-bars gg, then pass co-ordinate bar U, or its equivalent, through the mortise-hole of either guide- 10 bar g, through the horizontal opening of draw-bar B, into the mortise hole of the other guide-bar, and secure it therein as provided; place coupler A in said rest R, with the center section, D', of separable device in the 15 horizontal opening d' of said draw-bar B, with the upper and lower sections, D and D'', fitting closely and clutching firmly the horizontal ends of said draw-bar B; place in the vertical opening of said draw-bar B two springs, 20 as S S, with one right-angled end of each resting in the vertical mortise-hole through the center of co-ordinate bar U, or its equivalent, with the other angled end of one in the vertical mortise-hole O of the clutch end of separable device, and one right-angled end of the other spring S upon the bar-key i, behind and between it and the horizontal end of the guide-rest I. To more firmly secure the combination in operation, place key h in the mortise-hole O of the clutch-end separable device of 25 the coupler A, in front of and upon the angle of spring S, and secure it with the small rod p, or equivalent, fastened in the holes provided. Cars, engines, and tenders thus provided, 30 one having the link L secured at one end within the cavity a of the coupler A, with the pin P therein, the outer end of said link is elevated and held within the radius of its opening by the quarter-circle walls A' and A''. If 35 a greater elevation is desired, place the end of link in its rest a'. The other pin P is seated, as at N, in the opposite coupler A, Fig. 2. When the couplers are brought in contact upon the same plane or the former upon a 40 higher plane within the radius of the opening of the link-cavity, the link L, striking within the radius of said opening, is directed and guided by the convex converging quarter-circle walls A' and A'' to and within cavity 45 a. The circular front of the coupling coming in contact each with the other immediately unseats the pin P and it drops through the link L, and the coupling is made automatically. The springs S S, yielding to the 50 force of contact between the couplers A, the draw-bars B recede, extending the rear springs and compressing the front springs of each combination. Forward movements actuate the reverse operation of said springs S S, providing for the movements of the draw-bar B,

elastic resistance preventing violence and injury, and substituting therefor safety and comfort.

Inasmuch as the coupling-link L and pin P, made in accordance with my invention, are 65 abstractly common in form, I do not claim such, broadly; but

What I do claim, and desire to secure by Letters Patent, is—

1. The combination, in a separable coupling 70 combination, of a separable coupler having a coupling-link, L, and pin P, a circular front to link-opening having quarter-circle walls A' and A'', converging from the contour of said front blending with the semicircle and three-quarter-circle walls of inner cavity a, of elliptical form, and link-rest a' of crescent form, a pin-hole, H, with seat N, and a clutch end separable device having three sections, the central one with a vertical hole through its 80 center, or equivalents, all substantially as and for the purposes specified. 75

2. In a separable coupling combination, the draw-bar B, having a vertical and a horizontal opening, each equal and bisecting the other longitudinally, provided with the guide-rest I, secured to the vertical end of said draw-bar with bar-key i, and mortise-holes provided therefor, or equivalents, all substantially as and for the purposes specified. 85

3. In a separable coupling combination, the crimp-spring S, having depending right-angled ends with a hole through each provided with a small rod, chain, or other equivalent for security, and a separable pin, h, with a hole 95 through its lower end, all substantially as and for the purposes set forth. 90

4. In a separable coupling combination, the attachment having connecting-bars C C with angles 1 2 3 front, and C' C'' rear, and a mortise-hole in the vertical side of angles 1 and C' of each, guide-bar g, with a tenon on the ends of each and a mortise-hole through each equally distant from the corresponding ends, a co-ordinate bar, U, with a mortise-hole through 100 each end provided with pins, bolts, keys, or other means of security, and a mortise-hole 105 vertically through its center, or an equivalent bar, and a coupler-rest, R, having the form of a rectangle parallelogram or other required form, all substantially as and for the purposes specified. 110

5. The combination, in a separable coupling combination, of the coupler A, draw-bar B, springs S, and attachments, all substantially 115 as set forth.

JAMES R. AVERY.
